UNITED STATES PATENT OFFICE.

SAMUEL HELLER, OF NEW YORK, N. Y.

DESIGN FOR A PRECIOUS, SEMIPRECIOUS, OR SYNTHETIC STONE, OR AN IMITATION THEREOF.

50,444.

Specification for Design.

Patented Mar. 13, 1917.

Application filed October 30, 1915. Serial No. 58,919. Term of patent 7 years.

To all whom it may concern:

Be it known that I, SAMUEL HELLER, a citizen of the United States, residing at the borough of Manhattan, in the city, county, and State of New York, have invented a new, original, and ornamental Design for a Precious, Semiprecious, or Synthetic Stone, or an Imitation Thereof, of which the following is a specification, reference being had therein to the accompanying drawings, which form a part thereof.

In the drawings:—

Figure 1 is a plan view of a cut stone embodying my design;

Fig. 2 is a side view thereof; and

Fig. 3 is an end view thereof.

I claim:—

An ornamental design for a precious,

semi-precious, or synthetic stone, or an imitation thereof consisting of a crown cutting having a parallelogrammatic table, a trapezium shaped facet extending downwardly toward the girdle at each side of said table, and two scalene triangular facets at opposite sides of the crown, the short sides of said triangular facets being coincident, another of the sides of each of said triangular facets being coincident with one of the sides of the adjoining trapezium shaped facet, and the remaining side forming a part of the girdle and a pavilion having facets thereon.

SAMUEL HELLER.
